INTERCHANGEABLE OR REVERSIBLE
EARRING

Samuel Friedman, Brooklyn, N. Y.

Application June 29, 1949, Serial No. 101,969

2 Claims. (Cl. 63—14)

1

This invention relates to an interchangeable or reversible ear ring.

It is an object of the present invention to provide an ear ring which can be easily adapted to display different surfaces thereof depending upon the time of day the ear ring is worn by the wearer, one display would be used during the day while the other would be used during the evening, the operation requiring only the reversing of the ear ring or the changing of parts of the same.

It is another object of the present invention to provide simple parts which are detachable from one another by which to effect the reversing of the ear ring and wherein the change over from one display of the ear ring to the other can be effected by the simple detachment of the arrangement of the parts to extend in different directions.

Other objects of the present invention are to provide an interchangeable or reversible ear ring which is of simple construction, inexpensive to manufacture, easy to attach to the ear, easy to interchange the parts, compact, of pleasing appearance and efficient in operation.

For other objects and for a better understanding of the invention, reference may be had to the following detailed description taken in connection with the accompanying drawing, in which

Fig. 1 is a perspective view of one form of the invention embodying the features of the present invention wherein the spring clips are arranged on the opposite sides of the piece and adapted to cooperate with one another to engage the opposite sides of the ear whereby to retain the ear ring in place upon the ear.

Fig. 2 is a perspective view of the form of the invention shown in Fig. 1 with the retaining clips sprung outwardly and looking upon the reverse side of the ear ring.

Fig. 3 is a perspective view of a modified form of the ear ring wherein the clip is removable from the ring and adapted to be placed on one side or the other thereof and which is engageable with the ear ring itself to maintain the ear ring in place upon the ear.

Fig. 4 is a side elevational view of the ear ring.

Fig. 5 is a sectional view of the ear ring taken on line 5—5 of Fig. 4 with the clip head sprung downwardly.

Fig. 6 is a sectional view of the clip removed from the ear ring.

Fig. 7 is a sectional view of the clip removed from the ear ring, but with the parts sprung upwardly as in a retaining position.

2

Fig. 8 is a fragmentary and sectional view of the clip and showing the spring retaining portion thereof in dotted line position and in a manner to retain the clip upon the ring.

5 Fig. 9 is a perspective view of a still further form of the invention.

Fig. 10 is a perspective view of the form of the invention shown in Fig. 9 and as viewed from a different direction.

10 Fig. 11 is a vertical sectional view taken on line 11—11 of Fig. 10.

Fig. 12 is a fragmentary sectional view similar to Fig. 11, but with the main parts unfastened from one another.

15 Fig. 13 is a vertical sectional view of a still further form of the invention wherein there is a central fastening piece to which the opposite parts are attached.

Fig. 14 is a collective view of the several parts 20 of the form of the invention shown in Fig. 13.

Referring now particularly to Figs. 1 and 2, there is shown an ear ring having a body 15 with a decoration on one side of the same including jewels 16 adapted for evening wear. On this side of the ring there is soldered, or otherwise connected, a main clip part 17 having a spring arm 18 pivoted thereon, the upper end of which extends above the top of the main body and has a surface 19 for engagement with one side of the ear.

30 The opposite side of the main body has a different appearance, as seen in Fig. 2, and is decorated with carvings or embossings 21 and 22 and on this side is a main part 23 which carries a spring arm 24 operated and held in an upward position by a spring 25 in a manner to be more clearly described in connection with the other forms of the invention. This arm has an ear engaging surface 26 and as both of these arms

35 18 and 24 are elevated they will engage the opposite sides of the ear to retain the ear ring in a suspended position therefrom. It will be apparent that this ring is reversible and can be worn so that either one face or the other will

40 be on the outside. The clips are made of precious metal or plated to blend with the styling or color of the faces of the main body.

45 Referring now particularly to Figs. 3 to 8 inclusive, there is shown a modified form of the invention wherein but one clip arrangement is used. In this form of the invention, there is provided a main ear ring body 31 having a different colored face on the opposite sides thereof and in the bottom thereof an opening 32 upwardly through which a spring catch portion 33

of a substantially L-shaped part 34 may be projected. Upon the upper end of the part is a spring clip arm 35 having a spring 36 engaging with a projection 37 on the part 34 above its pivotal connection 38 therewith. The upper end of the arm has an engaging surface 39 which will engage one side of the ear to press the ear against the outer part of the main body 31 in the manner as shown in Fig. 4 to secure the ring to the ear lobe 41. The part 34 with the spring arm can be easily detached from the opening 32 or inserted therein in the manner as shown in Fig. 8 with little difficulty. The part 34 is so shaped to extend up either side of the ear ring and to cooperate with the body 31 to retain the same upon the ear 41 of the wearer. The spring arm 39, when it is withdrawn from the body 31, will assume the position shown in Figs. 5 and 6 and when the same is elevated will assume the position shown in Figs. 3 and 7. The part 34 with the arm 35 can be easily withdrawn and located in a reverse direction upon the body 31.

Referring now particularly to Figs. 9 to 12, there is shown a still further form of the invention wherein the body is made of separable parts 43 and 44. The part 43 is provided with a recess 45 to receive the part 44. In the recess is a male fastener element 46 for receiving a cooperating female fastener element 47 of the part 44. These parts can be kept in sets displaying different surfaces and can be made up at the desire of the user. On each part there is fixed a clip, indicated generally at 48, and having an ear engaging face 49. This clip has a main part 51 which is secured by welding or soldering, as indicated at 52, to the part. The part 44 has a similar clip 53 connected to it by a fixed part 54.

Referring now particularly to Figs. 13 and 14, there is shown a still different form of the invention wherein there is an intermediate part 61 having female fastener elements 62 and 63 extending from the opposite sides thereof. Each of the ear ring body parts, as indicated at 64 and 65, has a male fastener element 66 adapted to engage with the female fastener element 62 or 63. The decoration on the parts 64 and 65 will be different and these parts will be kept in sets and can be assembled as desired by the use of the intermediate part 61 to form the completed ear ring. On each part 64 or 65 which is different from one another only in the decoration thereon, there is a spring clip rigid part 67 secured to the ear ring body part and a spring arm part 68 hinged to the part 67 by a pin 69 and having an engaging end surface 71. The engaging surfaces of the respective parts will engage with the opposite sides of the ear lobe to retain the ear ring in place thereupon.

It should be apparent that there has been provided an interchangeable or reversible ear ring whereby two surfaces can be had upon the ear ring so that the same can be readily adapted for either afternoon or evening wear by a simple procedure of reversing the ear ring or the spring clip associated therewith. The assembly, as shown in Figs. 9 and 13, can be made up differently each day of different sets of parts. The user will have a collection of several different styles, any two of which can be secured together or taken with one another according to the user's fancy. The spring clips are either made rigid with the body or are removable, as shown in the form of the invention in Fig. 3.

While various changes may be made in the detail construction, it shall be understood that such changes shall be within the spirit and scope of the present invention as defined by the appended claims.

What is claimed is:

1. A reversible ear ring comprising a main body, said main body having an upwardly enlarged bottom opening therein, a two part adjustable spring clip having a substantially L-shaped attaching part and an upwardly extending retaining part engageable with the ear and adapted to cooperate with the main body to retain the ear ring upon the ear, said substantially L-shaped attaching part of the clip having one leg and adapted to enter the body bottom opening and the other leg extending laterally from said opening to one side of the body or to the other side of the body, said L-shaped attaching part having releasable retaining means cooperable with the wall of said opening to normally retain the adjustable spring clip against downward displacement from the body, said L-shaped attaching part in said opening being of polygonal section to retain the attaching part when in the opening against rotational displacement, whereby said spring clip can be reversed upon the main body to permit either one side of the body to lie on the outer side of the ear or the other side of the body to lie on the outer side of the ear.
2. A reversible ear ring comprising a main body, said main body having an upwardly enlarged bottom opening therein, a two-part adjustable spring clip having a substantially L-shaped attaching part, and an upwardly extending retaining part engageable with the ear and adapted to cooperate with the main body to retain the ear ring upon the ear, said substantially L-shaped attaching part of the clip having one leg and adapted to enter the body bottom opening, and the other leg adapted to extend laterally from said opening to one side of the body or to the other side of the body, said L-shaped attaching part having releasably retaining means cooperable with the wall of said opening to normally retain the adjustable spring clip against downward displacement from the body, said releasable retaining means comprising a laterally resilient detent means, whereby said spring clip can be reversed upon the main body to permit either one side of the body to lie on the outer side of the ear or the other side of the body to lie on the outer side of the ear.

SAMUEL FRIEDMAN.
